UNITED STATES PATENT OFFICE

WILLIAM A. READY, OF BROOKLINE, MASSACHUSETTS

D-HANDLE

Application filed September 4, 1930. Serial No. 479,666.

My invention aims to provide improvements in D-handles for shovels and the like and the method of assembling the casing with a stale.

Reference is hereby made to a divisional of this application Serial No. 521,181, filed March 9, 1931.

In the drawing which illustrate a preferred embodiment of my invention:—

10 Figure 1 is an elevation view of my invention showing the upper end of a split stale incased in a sheet metal casing, parts of the casing structure being shown in dotted lines; Fig. 2 is a view of the sheet metal casing 15 before attachment to a stale, the lower portion being in cross-section to show the means which holds the parts of the casing in assembled relation, the reinforcing portions on the inner flanges being shown in their positions 20 before being bent;

Fig. 3 is a section taken on the line 3—3 of Fig. 2;

Fig. 4 is a view of the lower portion of the metal casing showing one method of assembling the stale therewith to bend the reinforcing portion during the assembling operation; and

Fig. 5 is a view of the lower end of one part of the casing as viewed when looking toward 30 the flat face thereof.

With reference to the drawing, I have shown a D-handle which includes a casing 1 preferably formed from sheet metal and combined with the split end of a stale 2 and a grip 35 piece 3, as shown in Fig. 1. The general construction of the handle, except for the means by which the casing parts are secured together, and the method of assembly of the three parts of the handle is substantially the 40 same as shown and more fully described in my co-pending application Serial No. 341,131, filed February 19, 1929. Since my present invention relates to improvements in the casing and a method of assembling the stale with the 45 casing to bend the reinforcing members as a part of the assembly operation it will not be necessary to describe in detail the general construction of the handle and the method of assembly. Furthermore, my present invention is similar in construction to my co-

pending application Serial No. 479,665, filed herewith, and over which the present invention is an improvement. Therefore, I shall describe only so much of my device as is necessary for a clear understanding of my present 55 invention over the devices and methods more fully explained in the applications referred to above.

The sheet metal casing 1 illustrated in the drawing is formed from two similar hollow 60 sheet metal parts each of which is substantially semi-cylindrical in cross-section and is provided with a flat face formed by flanges 4, 4 bent inwardly and abutting at the center, as shown in Figs. 3 and 4. These inwardly 65 bent flanges 4, 4 terminate a substantial distance from the stale-receiving end of the casing, Figs. 2 and 5, thereby leaving the lower portion open so that when the two pieces are secured together there will be no partition in 70 the center of the casing at the stale-receiving end thereof, as clearly shown in Fig. 2. Each casing part is also provided with a vertical flange 5 at one end of the lower semi-cylindrical portion, while a reinforcing portion 6 75 is provided at the lower edge of that flange 4 which is located at the opposite side of the vertical axis of the casing part, the purposes of which will be more fully hereinafter described.

The two parts of the casing are assembled together, Fig. 2, in such a manner that the flat face of one part faces the flat face of the other part. Furthermore, the flange 5 of one part overlaps the cylindrical portion of the 80 other part, Fig. 3, and each is welded to secure the parts of the casing in fixed assembly. Each reinforcing portion 6 extends below a flange 4 and projects into a space provided by the D-shaped cross-section of a casing 85 part. These reinforcing portions may be bent upwardly and against the inner faces of the flanges 4; as shown in Fig. 1, prior to insertion of the split stale or, as will hereinafter be described, may be bent as a part 90 of the assembly operation. The reinforcing portions 6 are provided to prevent spreading of the arms of the casing beyond the lower edges of the flanges 4 when the casing is 95 spread into Y-shaped formation, as shown in 100

Fig. 1. The reinforcing portions 6 also help to prevent accidental splitting of the stale when the handle is subjected to undue stress, such, for instance, as when the handle is used 5 for a "pry".

The casing which is illustrated and described in my present application is decidedly stronger adjacent to the stale-receiving end than the casing shown and described in my 10 above-mentioned co-pending application Serial No. 479,665, because of the arrangement of the vertical flanges 5 with relation to the reinforcing portions 6. As above stated each part of the casing has been so constructed 15 that the flange 5 is located below one of the flanges 4, while the reinforcing portion 6 is located at the lower end of the other flange 4. Thus, it is possible to provide larger flange 20 portions 5 and reinforcing portions 6, because no portion of one is taken from the flange from which the other is formed. The result is a larger welded area and larger, and therefore more durable, reinforcing portions.

The method of assembling the stale 2 with 25 the casing 1 is, in general, substantially the same as the method more fully illustrated and described in connection with my co-pending application Serial No. 341,181. There is an additional step in the method of assembly of 30 the parts of the present structure, however, inasmuch as the reinforcing portions may be very readily pressed from the position shown in Fig. 2 to the position shown in Fig. 1 by the ends of the arms of the stale 2 when forced 35 into the casing, as clearly shown in Fig. 4. When this method of assembly is followed, the reinforcing portions are clamped tightly between the inner faces of the flanges 4 and the sides of the arms of the stale and are, 40 therefore, back-supported.

My improved D-handle structure is strong, durable and relatively inexpensive both from a standpoint of simplicity of construction and reduction in the number of operations 45 required for assembly of parts of the casing and the stale therewith, especially when the method of upsetting the reinforcing portion is followed as above described.

While I have illustrated and described a 50 preferred embodiment of my invention, I do not wish to be limited thereto, because the scope thereof is best defined by the following claims.

I claim:

55 1. In a D-handle construction for shovels and the like, a metal casing composed of two similar parts secured together and adapted to receive a stale, each of said casing pieces having a flat inner face portion adjacent to the stale-receiving end, a reinforcing tab extending from the lower edge of the flat face over the lower edge of the other piece and against the inner surface thereof thereby to be hooked into engagement therewith, said reinforcing portion be-

ing located at one side of the vertical center of the casing piece and a vertical edge flange at the opposite side of the center adjacent to the stale-receiving end of said casing piece and overlapping said other casing piece and 70 rigidly secured thereto.

2. In a D-handle construction for shovels and the like, a metal casing composed of two similar parts secured together and adapted to receive a stale, each of said casing pieces 75 having a flat inner face portion adjacent to the stale-receiving end terminating a substantial distance from the stale-receiving end of the casing, a reinforcing tab extending from the lower edge of the flat face over the lower 80 edge of the flat face of the other piece and against the inner surface thereof thereby to be hooked into engagement therewith, said reinforcing portion being located at one side of the vertical center of the casing piece and a vertical edge flange at the opposite side of the center and located between the end of the flat face and the stale-receiving end of said 85 casing piece and overlapping said other casing piece and rigidly secured thereto.

3. In a D-handle construction for shovels and the like, a metal casing composed of two similar parts secured together and adapted to receive a stale, each of said casing pieces 90 having a flat inner face portion adjacent to the stale-receiving end formed by two flanges having their lower ends terminating in spaced relation to the stale-receiving end of the casing, one of said flanges having a reinforcing tab extending from its lower edge 100 and the other being free of any extension and a vertical flange extending along one edge of said piece between the stale-receiving end and the end of the flange free from any extension, thereby permitting said vertical 105 flange and said reinforcing portion being made of such dimensions as may be desired without interfering with each other.

4. A casing for a D-handle structure comprising two similar sheet metal parts each 110 having two flanges providing a flat inner face portion adjacent to the stale-receiving end, a reinforcing portion extending from the lower edge of one of said flanges at right angles thereto before the casing is attached 115 to a split stale and adapted to be bent over the edge of a flange of the other part of the casing as and for the purposes illustrated and described.

5. A casing for a D-handle structure comprising two similar sheet metal parts each having two flanges providing a flat inner face portion adjacent to the stale-receiving end, a reinforcing tab extending from the lower edge of one of said flanges at right angles 120 thereto before the casing is attached to a split stale and adapted to be bent over the edge of a flange of the other part of the casing as and for the purposes illustrated 125 and described and a vertical flange on each 130

part overlapping the other part and welded thereto at the stale-receiving end of said casing.

6. A casing for a D-handle structure comprising two similar sheet metal parts each having two flanges providing a flat inner face portion, a reinforcing portion extending from the lower edge of one of said flanges at right angles thereto before the casing is attached to a split stale and adapted to be bent over the edge of a flange of the other part of the casing as and for the purposes illustrated and described and a vertical flange on each part overlapping the other part and welded thereto at the stale-receiving end of said casing, the reinforcing portion of one part being located at that side of the center of the casing at which the vertical flange of the other part is located as and for the purposes illustrated and described.

7. A sheet metal casing for a D-handle comprising, in combination, two similar parts substantially D-shaped in cross-section throughout the greater portion of their lengths, said parts being secured together adjacent to the stale-receiving end by means of vertical flanges of substantial width welded to opposed parts and reinforcing hook-like means provided by each part adjacent to the upper ends of the flanges and the reinforcing portion of one part being located at that side of the center of the casing at which the vertical flange of the other part is located as and for the purposes illustrated and described.

8. In a D-handle construction for shovels and the like, a metal part composed of two similar pieces secured together and adapted to be attached to a stale, each of said pieces of the metal part having opposed inwardly bent flange portions, a reinforcing portion extending from the lower edge of a flange of one of said pieces over a lower edge of a flange of the other piece and against the inner surface thereof, said reinforcing portion being located at one side of the vertical center of the metal part and a vertical edge flange at the opposite side of the center adjacent to the stale-receiving end of said piece and overlapping said other piece and being rigidly secured thereto.

In testimony whereof, I have signed my name to this specification.

WILLIAM A. READY.
